US00D580344S

(12) **United States Design Patent**
Wai

(10) **Patent No.:** US D580,344 S
(45) **Date of Patent:** ** Nov. 11, 2008

(54) **HELICOPTER ROTORS, BLADES AND SHAFTS**

(75) Inventor: **Chi Pok Billy Wai**, Quarry Bay (HK)

(73) Assignee: **Silverlit Toys Manufactory, Ltd.**, Hong Kong (HK)

(**) Term: **14 Years**

(21) Appl. No.: **29/303,199**

(22) Filed: **Feb. 1, 2008**
